UNITED STATES PATENT OFFICE.

FREDERICK WILLIAM MASON, OF TORONTO, ONTARIO, CANADA.

GREASE AND OIL SEPARATOR.

1,377,906.

Specification of Letters Patent. Patented May 10, 1921.

Application filed August 30, 1918. Serial No. 252,125.

To all whom it may concern:

Be it known that I, FREDERICK WILLIAM MASON, a citizen of Canada, residing at city of Toronto, in the county of York and 5 Province of Ontario, Canada, have invented new and useful Improvements in Grease and Oil Separators, of which the following is a specification.

My invention relates to improvements in 10 grease and oil separators, and is primarily intended for recovering grease from the liquid discharged from digesters, presses, and the like used in packing houses and rendering plants, though of course it may also 15 be employed anywhere where grease or oil is to be reclaimed such as in the case of overflow from crank cases of engines.

In packing houses it is customary to convey the liquids from the digesters, presses 20 and the like to a catch basin, where the grease is allowed to settle and is removed by hand skimming. Where separators have been employed it has usually been found either that too much grease has been dis- 25 charged with the water and lost, or else too much water has been drawn off with the grease. One of the great troubles has been that a foaming condition has been set up in most of the separators that have been tried, 30 this of course renders proper separation impossible.

The essential features of my invention consist in the provision of a vessel divided 35 into a series of chambers in which the means of communication between the said chambers comprises water pipes arranged substantially vertically and in close proximity to the partition dividing that chamber from the next; the top end of each pipe is open 40 and terminates substantially flush with the top of the sides of the vessel, and the open bottom ends of the pipes are graduated in height, each one lower than the last; each discharge from the said pipes into the next 45 chamber is graduated in height each one higher than the last. The means of communication for the oil from one chamber to the next consists in a series of horizontally arranged pipes on substantially the same 50 horizontal plane and each having a T-attachment arranged at its discharge end which may be turned either vertically or at varying angles to the vertical. The oil discharge pipes must also be at a higher level 55 than the last water discharge pipe.

The objects attained by this form of con-

struction are: firstly, the water pipes are anti-siphon pipes on account of their upper ends being always open to the atmosphere and consequently, the possibility of foaming 60 is precluded; secondly the T-attachments naturally discharge the oil through the upper side and the water through the lower side; and thirdly the adjustability of the T-attachments permits of adjustment to handle 65 varying heights of liquid in the various chambers.

My invention is more fully described with the aid of the accompanying drawings in which similar parts are similarly designated 70 in all the views;

Figure 1 shows a sectional elevation, on the line 1—1 of Fig. 2.

Fig. 2 a plan,

Fig. 3 a section on the line 3—3 of Fig. 2, 75 and

Fig. 4 a section on the line 4—4 of Fig. 2.

Referring now more particularly to the drawings, 36 designates a separator, preferably of rectangular shape, divided into 80 chambers 4, 3, 2, 1 and 8 by the partitions 5, 6, 7, and 9. In the first chamber 4 I provide one or more removable strainers or baskets 15, having outlets on their undersides of sufficient size to allow liquid to pass freely 85 through, but which will retain any solids; for this purpose I prefer to employ expanded metal or wire netting of suitable mesh. The said strainers 15 rest on supports 37, 37^a. From the outer support 37^a I 90 arrange a deflecting plate 38, with openings 19 arranged in its upper end.

In the chamber 4 I also supply a vertical water pipe 17 extending downward from a height substantially level with the top of the 95 sides of the said chamber to approximately level with the bottom of the deflecting plate 38. The said pipe 17 is open at both ends and has a horizontal branch 18 which passes through the partition 5 into the chamber 3. 100 The horizontal oil pipe 20 arranged above the level of the branch 18 also connects the chambers 4 and 3, and has a T-attachment 39, with upper and lower outlets 21 and 22 respectively, at its discharge end. 105

Similarly in the chambers 3 and 2 vertical water pipes 23 and 28 with horizontal branches 24 and 29 connect with the chambers 2 and 1 respectively. And also in the said chambers 3 and 2 vertical oil pipes 25 110 and 30 enter into the chambers 2 and 1 respectively where the said pipes 25 and 30

terminate in T-attachments 40 and 41, having top outlets 26 and 31, and bottom outlets 27 and 32 respectively.

In the chamber 1 I provide an oil funnel 12, the lower end of which is preferably provided with a set screw 13 so that the height of the said funnel may be regulated up and down the upper end of the oil discharge pipe 11 which passes through the outer wall 42 of 10 the chamber 1.

From the chamber 1, and toward the bottom thereof, the inlet 33 of the water pipe 10 passes through the partition 9 and terminates in the tell-tale chamber 8 at a height 15 slightly below the level of the top of the funnel 12 when in its bottom position in the chamber. The water discharge pipe 34 in the tell-tale chamber 8 is similarly arranged to the pipes 28, 23, and 17 in that it is open 20 at both top and bottom, the top thereof being substantially level with the top of the sides of the chamber 8, and the bottom in close proximity to the bottom of the chamber 8. The pipe 34 has a water discharge branch 35, which passes through the side 42 of the said chamber 8, the height of the said branch 35 being slightly below the level of the top of the pipe 10. The operation of the separator is as follows:

30 Liquid is emptied into the removable strainer 15 where any solids are retained, and the liquid passes down into the space 14 between the deflecting plate 38 and outer wall 43, and through the outlet 16 into the 35 main portion of the chamber 4. Along the upper end of the deflecting plate 38 I supply a series of holes as shown at 19 which permit of oil passing out into the chamber 4 without going down through the outlet 16. 40 These holes allow the oil to get away which might otherwise be kept up in the space 14 while the water escaped through the outlet 16.

Once the liquid is in the chamber 4 the oil 45 tends to rise and the water naturally gravitates toward the bottom. The oil passes through the oil pipe 20 into the T-attachment 39 where it strikes against the end of the said T; here the oil tends to rise and 50 flow out through the upper outlet 21, and any water that may have been carried along with the oil tends to fall and passes out through the lower outlet 22, both into the chamber 3.

55 The water rises up the pipe 17 and passes along the branch 18 into the chamber 3 where it enters at a lower level than the pipe 20. If any oil has come through the water pipe with the water it will then rise 60 in the chamber 3 to the oil level. And it is for the reason that less oil will pass through the water pipes in the succeeding operations that the branches in the third and fourth chambers are at gradually falling levels.

65 The oil pipes 25 and 30 with their T-

attachments 40 and 41 respectively operate similarly to the oil pipe 20 with its T-attachment 39. The three oil pipes 20, 25, and 30, are substantially on the same horizontal plane.

The water pipes 23 and 28 with their branches 24 and 29 operate similarly to the pipe 17 and branch 18, though each succeeding pipe 23 and 28 extends lower down in their respective chambers as in each succeeding operation there is less oil entering the water pipes with the water.

On account of the fact that the water pipes 17, 23, and 28 are open at their upper ends to the atmosphere at all times there is no possibility of siphonic action from chamber to chamber. This has been the cause of foaming in other forms of separators as air has been in that way mixed with the water and oil and consequently proper separation has been impossible.

The T-attachments 39, 40, and 41, are rotatably mounted on their respective oil supply pipes so that they may be inclined at varying angles to the vertical. This is of assistance because when the top of the oil is below the discharge level of the upper side of the T-attachment when in vertical position, the latter may be turned to such an angle that the discharge level will be lowered, and the oil allowed to flow from one chamber to the next.

When the liquid reaches the chamber 1 thorough separation has taken place. The oil is then drawn off through the funnel 12 and oil discharge pipe 11. The object of having the height of the said funnel adjustable is so as to be able to take care of spasmodic feeding when the height of the liquid may be suddenly raised, in which event some of the water might get into the oil discharge funnel. The height of the oil funnel of course normally regulates the height of the liquid in the tank.

The use of the tell-tale chamber is not essential to the operation of the device, but its use is very desirable, because any oil that is escaping with the water would immediately be detected by the operator. And also because the arrangement of the piping into and from the said chamber practically guarantees that no oil will escape. Firstly it would have to drop to the bottom of chamber 1 to enter the inlet 33 of pipe 10, and it would then again have to drop from the high discharge level of the side pipe 10 to the bottom of the tell-tale chamber to enter the inlet of the water discharge pipe 34. And this the oil could not do.

In fact by experiments it has been conclusively shown that either water or oil alone can be passed through the separator and that they will be discharged only through their respective discharge pipes.

Throughout the foregoing specifications

I have referred to the oil pipe; this of course means oil and grease pipes in apposition to water pipes which latter term refers to pipes to convey the resultant liquid 5 from which the liquid fatty matter is being or has been recovered.

When this device is being employed in packing houses and rendering plants for separating grease the latter is usually 10 handled at a temperature of from 160 to 200 degrees Fahrenheit.

In the foregoing I have described a four-chamber separator. The number of chambers however may be varied.

15 Moreover certain alterations and modifications may be made in the construction of the invention provided the said alterations and modifications fall within the scope of what I claim.

20 What I claim is:—

1. A grease and oil separator comprising a vessel divided by partitions into a plurality of chambers, water conducting means connecting each chamber with the one next 25 to it, said water conducting means consisting of vertical pipes open at both ends, the upper ends of said pipes terminating substantially flush with the top of said chambers and their lower ends extending some 30 depth into their respective chambers, said pipes each having a substantially horizontal branch extending through the adjacent partitions into the adjoining chambers and oil pipes connecting each chamber with the one 35 next to it, in combination with separate water and oil discharge pipes.

2. A grease and oil separator comprising a vessel divided by partitions into a plurality of chambers, water conducting means 40 connecting each chamber with the one next to it, said means consisting of vertical pipes having their lower ends graduated in height each one lower than the last, said pipes each having a substantially horizontal branch 45 extending through the adjacent partition into the adjacent chamber, said vertical branches being graduated in height each branch being on a higher horizontal plane than the last, and substantially horizontal 50 oil pipes connecting each chamber with the one next to it in combination with separate water and oil discharge pipes.

3. A grease and oil separator comprising a vessel divided into a plurality of chambers, 55 water conducting means connecting each chamber with the one next to it, and vertically arranged oil pipes connecting each chamber with the one next to it, each of said oil pipes having T-attachment arranged on 60 its discharge end, in combination with separate water and oil discharge pipes.

4. A grease and oil separator comprising a vessel divided by partitions into a plurality of chambers, suitable piping connect- 65 ing each chamber with the one next to it, an

oil discharge arranged in the final chamber, in combination with a tell tale chamber, connected to said final chamber by a pipe having an inlet in close proximity to the base of said final chamber and discharging in 70 said tell tale chamber below the level of said oil discharge, and a final water discharge.

5. A grease and oil separator comprising a vessel divided into a plurality of chambers, water connecting means consisting of anti-siphon pipes connecting each chamber with the one next to it, and horizontal oil pipes also connecting each chamber with the one next to it, said oil-pipes having adjustable T-attachments at their discharge ends in 80 combination with separate oil and water discharging means.

6. A grease and oil separator comprising a vessel divided into a plurality of chambers, the first or receiving chamber having a 85 strainer in the upper portion thereof, said strainer draining into a portion of said first chamber separated from the main body thereof by a deflecting plate terminating some distance from the bottom of said 90 strainer, said deflecting plate being provided with perforations toward the upper end thereof, in combination with vertical water pipes arranged in said chambers said water pipes being open at both ends and each having a substantially horizontal branch terminating in the next chamber in sequence; and horizontal oil pipes having T-attachments at their outlet ends connecting each chamber to the next chamber in sequence, in 100 combination with separate oil and water discharge-pipes.

7. A grease and oil separator comprising a vessel divided by partitions into a plurality of chambers, water conducting means 105 connecting each chamber with the one next to it, said water conducting means consisting of vertical pipes open at both ends, said top ends terminating substantially level with the top of said chambers, and said bottom 110 ends graduated in height each one lower than the last, said pipes each having a substantially horizontal branch terminating in the next chamber in sequence, each of said branches being on a higher horizontal plane 115 than the last, and horizontal oil pipes on substantially the same level connecting the chambers each with the one next to it in sequence, said oil pipes being on a higher horizontal plane than the last water discharge pipe, in combination with separate oil and water discharge pipes.

8. A grease and oil separator comprising a vessel divided by partitions into a plurality of chambers, water conducting means 125 connecting each chamber with the one next to it in sequence, and horizontal oil pipes connecting each chamber with the one next to it in sequence, said oil pipes having means whereby the oil discharge level may be regu- 130

lated, in combination with a final oil discharge, the height of which may be also varied, and a water discharge.

9. A grease and oil separator comprising in combination, a strainer, a receiving passage from said strainer, oil outlet holes in side of said passage, a main outlet at bottom of said passage into the first of a series of chambers, each chamber having both anti-siphon water pipes and oil pipes with adjustability, as to their discharge level com-

municating with the next chamber in sequence, a final oil discharge of adjustable height, a tell tale chamber connected by a water pipe from final chamber, and an anti-siphon pipe to discharge the contents from said tell tale chamber. 15
